UNITED STATES PATENT OFFICE

95,939

DESIGN FOR A CABLE CLAMP

Cyril H. Thomas, Chicago, Ill.

Application February 1, 1935, Serial No. 55,202

Term of patent 7 years

To all whom it may concern:

Be it known that I, Cyril H. Thomas, a citizen of the United States, residing at 619 E. 40th Street, Chicago, Cook County, Illinois, have invented a new, original, and ornamental Design for Cable Clamp, of which the following is a specification, reference being had to the accompanying drawing, forming part thereof, in which:

Fig. 1 is a front perspective view of a cable clamp showing my new design;

Fig. 2 is a front elevation; and
Fig. 3 is a perspective view of the same from another angle to that of Fig. 1.

I claim:
The ornamental design for a cable clamp as shown.

CYRIL H. THOMAS.
